UNITED STATES PATENT OFFICE.

FRANK HAWORTH, OF NOTTINGHAM, ENGLAND.

PAPER-HANGING APPARATUS.

Application filed December 8, 1920, Serial No. 429,141. Renewed July 3, 1922. Serial No. 572,677.

To all whom it may concern:

Be it known that I, FRANK HAWORTH, a subject of the King of Great Britain, and resident of Nottingham, England, have invented certain new and useful Improvements in Paper-Hanging Apparatus, of which the following is a specification.

This invention relates to improvements in apparatus for use in pasting and hanging wall-paper, and its object is to facilitate this operation.

According to this invention, the apparatus comprises a framing which is adapted to hold the paper in such a position that it can be readily applied to a wall or ceiling, means for raising the paper up and over the said frame, and means for simultaneously applying the paste thereto ready for transferring to the wall.

20 In the accompanying drawings:—

Fig. 1. is a front elevation, and

Fig. 2. a sectional side elevation of paper hanging apparatus constructed according to my invention.

25 Fig. 3. is a cross sectional elevation, and Fig. 4. a plan drawn to a larger scale than Figs. 1. and 2.

Fig. 5. is a side elevation of the top of the supplementary elevating frame drawn to the 30 same scale as Figs. 3. and 4.

Like letters indicate like parts throughout the drawings.

The apparatus comprises a base framing A with legs to stand on the ground, and 35 this base framing supports a vertical framing B, which may be of any desired height, and is disposed at the back of the base framing. If preferred the legs of the framing A may be provided with castors for convenience in moving it about.

In front of the base framing A is a roller or rod C, carried by brackets C', on which a roll of wall-paper D is placed (see Fig. 3.) and on top of the framing A is a paste tank E, in connection with which either one, or as 45 shown, two feed rollers F, F' are provided. The brackets C' may be adjustable to suit rolls of paper of different widths.

The feed rollers F, F' are mounted in 50 bearings in the framing A, they run in the paste contained in the tank E, and supply it to the paper D which is carried from the roll on the rod C over the said rollers F, F'. The paper C is held in contact with the roll-

ers F, by means of an idle roller or rod G 55 carried by slotted brackets C'.

Any other equivalent device may be used for applying paste to the paper besides the smooth rollers shown in the drawings.

One of these rollers F is provided with 60 two pulleys H, one at each end, (see Fig. 4.) and the journal at one end is fitted with a crank handle J for rotating it. The roller F' is connected to the roller F preferably by means of pulleys K on their respective journals, and a belt K', so that both are rotated together.

At the top of the vertical frame B is a roller L, (see Figs. 3 and 4) and at the lower part is a second L'. Carried from 70 each of the pulleys H on the roller F, is a belt or endless cord or tape N. Each of these tapes is carried from its pulley H under the roller L' up the frame B, over the roller L at the top, then down the frame 75 B again under an idle pulley L' below the roller L' and back to the pulley H.

The end of the roll of paper D is connected to the tapes N near the roller F, by clipping it to a rod O (see Fig. 1.), which 80 rod is provided with hooked ends which can be inserted in the respective tapes N, and said paper D is then carried under the roller L' up the frame B and over the roller L at the top, by rotating the roller F by means 85 of the crank handle J on the latter. At the same time paste is applied to one face of the paper by the rollers F, F' ready for transferring to the wall.

The rod O can by means of its hooked 90 ends, be connected to the tapes N at any required point, but if preferred said bar may be provided with clips for this purpose.

When a sufficient length of paper D has been pasted, this pasted portion can be severed from the main part, and disconnected from the tapes N, by removing it from the clips if required, by the following means.

At the front of the frame B is a supplementary frame P, which is attached to the 100 frame B by means of clamping guides B' on the latter. This frame P is provided with a rail P' at the top, which is made detachable, so that it can be removed and replaced, but in replacing it in position, it is moved to the 105 inside of the fold in the paper D, that is the fold formed by drawing it over the roller L, as shown in Fig. 3. The paper D can then

be raised to the required elevation by sliding the frame P up on the frame B, and fixing it at the required elevation.

The length of the pasted paper D supported on either the frame B or P or both, is then transferred to the wall by adjusting the apparatus with the frame B close up to the latter, and the paper can then be readily matched with the former length, and finally 10 pressed up to the wall. As shown in Fig. 1. of the drawings, one side member of the frame P has a scale of feet indicated upon it in order to assist the operator in cutting off the paper to the exact length required.

15 When papering a ceiling, the frame P is elevated until the rail P' is close up to the former, and the length of paper hanging down on each side of said rail P' can then be readily raised one after the other up to 20 and secured in the proper position on the ceiling.

The rail P' on the frame P is further divided in the middle, or at any other convenient point or points, and its ends are connected to parts P² which are pivoted on the top of the side members of the frame P, so that when the rail P' is disconnected in the middle, the respective parts form arms which can be swivelled round on the frame P. 25 In papering corners for instance, the length of pasted paper can be divided longitudinally, and each portion can be suspended from the corresponding part of the rail P', which latter can be adjusted so as 30 to hold the respective parts of the paper in the position required for hanging it in the corner.

When papering over an obstruction such as a fireplace, bars Q' which are adapted to 40 hold a rail Q some distance from the frame P, are substituted for the rail members P' as shown in Fig. 5. These bars Q' are attached to the pivoted parts P² on the top of the side members of the frame P, and the 45 rail Q, which is thus supported over the obstruction by the bars Q', is used to hold the paper close up to the wall.

The top of the frame B may be provided with detachable arms B⁴ which can be used 50 for papering in recesses and for holding lengths of pasted paper, when it is necessary to apply the paste some time prior to transferring to the wall.

If desired paper edge trimming mechanism of the usual construction may be combined with the apparatus described, and the process of trimming one or both edges of the paper can be carried on simultaneously with the operation of elevating and pasting 60 the paper.

This mechanism is disposed between the roll of paper D and the paste feed roller F, and as shown in the drawings, it comprises two parallel shafts R, R', mounted in bearings in or attached to the framing A. These

shafts R, R' are geared together by means of spur wheels R² R³ at one end, whilst the upper one R is geared to the roller F by means of toothed gear wheels S, S' (see Figs. 3 and 4).

If preferred, chain and sprocket, or belt gear may be used instead of the wheels S, S'.

The shafts R, R' described are provided with the usual circular cutters T, which can be set at any point in the length of the said 75 shafts R, R', and can be thus used for trimming the edges of the paper D or cutting it longitudinally into two widths as required. Sufficient cutters T may however be provided to perform both of the said operations 80 at one and the same time.

For working on staircases or like places, the respective sides of the framing A are provided with clamps V, (see Figs. 1 and 2) adapted to hold legs or supports W, which 85 are vertically adjustable therein, so as to provide a means of supporting the framing A level on a staircase or on other uneven surfaces.

In connection with the edge trimming 90 mechanism described, are adjustable brackets Y which are fixed on the framing A between the roll of paper D and the shafts R, R'. These brackets are adapted to engage with the edges of and guide the paper 95 D, and also serve to carry a rod Y' which holds the paper down between said brackets.

What I claim as my invention and desire to secure by Letters Patent is:—

1. In a paper hanging apparatus, a supporting frame, a tank for paste, a paste applying device arranged in the said tank and provided with a driving shaft, rollers on the end portions of the driving shaft outside the tank, guide rollers mounted in the frame, 105 endless flexible connections passing over the said rollers and guide rollers, a support for a supply of paper, and means for connecting the paper to the said flexible connections so that it is drawn over the top of the said paste 110 applying device.

2. In a paper hanging apparatus, a supporting frame, a tank for paste, a paste applying device arranged in the said tank and provided with a driving shaft, rollers on the 115 end portions of the driving shaft outside the tank, guide rollers mounted in the frame, endless flexible connections passing over the said rollers and guide rollers, a second paste applying device also arranged in the said 120 tank, a support for a supply of paper, means for connecting the paper to the said flexible connections so that it is drawn over the tops of the two paste applying devices, and means for pressing the paper downwardly 125 in its passage between the two paste applying devices so that its effective contact with them is assured.

3. In combination with a paper hanging apparatus as set forth in claim 1, a supple- 130

mentary frame slideable vertically on the said frame and adapted to raise the paper to a greater height and support it when raised.

4. In combination with a paper hanging apparatus as set forth in claim 1, a supplementary frame slideable vertically on the said frame and provided with side rails and a top rail formed in two parts, each of which parts is pivoted to one of the side rails and 10 adapted to be swung around horizontally.

5. In combination with a paper hanging apparatus as set forth in claim 1, mecha-

nism for trimming the paper arranged between the said support for the paper and the driving shaft so that the paper is 15 trimmed before being brought in contact with the said paste applying device.

In testimony whereof I have signed my name to this specification in the presence of two subscribing witnesses.

FRANK HAWORTH.
